UNITED STATES PATENT OFFICE.

ZACCHEUS SCOTT, OF WEST NEWTON, PENNSYLVANIA.

AUGER-BRACE.

No. 802,713.

Specification of Letters Patent.

Patented Oct. 24, 1905.

Application filed April 14, 1904. Serial No. 203,089.

To all whom it may concern:

Be it known that I, ZACCHEUS SCOTT, a citizen of the United States of America, residing at West Newton, in the county of Westmoreland 5 and State of Pennsylvania, have invented certain new and useful Improvements in Auger-Braces, of which the following is a specification, reference being had therein to the accompanying drawings.

10 This invention has relation to auger-braces, and has for its object the provision of a brace of novel character adapted to be used with any desired form or character of boring-tools.

The invention has for its further object the 15 provision of a breastplate of novel form which will relieve the person using the brace from the shock and jar incidental to such use.

The invention has for its still further object the provision of a novel antifriction-handle 20 whereby the brace may be revolved; and this invention has for its still further object the provision of a bit of novel form adapted to be employed in connection with my improved brace.

25 Having the above and other objects in view, as will hereinafter more fully appear, the invention consists in the novel construction, combination, and arrangement of parts hereinafter described and claimed.

30 I have illustrated my invention in the accompanying drawings, wherein—

Figure 1 is a side elevation, partly in section, of my improved brace with a breast-piece of circular contour applied thereto. Fig. 2 is a 35 vertical sectional view of the upper end of the brace and of part of the breast-piece shown in Fig. 1. Fig. 3 is a side elevation, partly in section, of a preferred form of breast-piece adapted to be applied to the brace shown in 40 Fig. 1. Fig. 4 is a side elevation of a sectional bit adapted to be used in connection with the brace shown in Fig. 1.

The shank 1 of the brace is of the usual shape, being a round section of metal bent twice at 45 right angles so as to form a crank, and the crank portion of the shank between the bends is formed with two annular grooves 2 and 3. A handle 4, which is fitted onto the shank before the bends are made in the same, is formed 50 with a central opening for the passage of the shank and with annular grooves 5 and 6 in its inner walls, said grooves coinciding with the grooves 2 3 in the shank. Balls 7 8 are arranged in the ways which are formed by the 55 coinciding grooves in the shank and in the handle, the said balls being put into the ways

through holes 10 11 in the handle, that after the balls have been introduced are closed by screw-plugs 12 13. The upper end of the shank is cone-shaped, as shown in Fig. 2, and 60 formed with an annular groove 14, that receives a thumb-screw 15 in the sleeve 16, which sleeve is fitted over the upper end of the shank and carries the knob 17, against which the person using the brace presses their hand or 65 body. A screw 18 is set in the sleeve 15 and carries a ball 19, which is socketed in a suitable cavity in the end of a screw 18 and bears against the end of the shank, so as to afford an antifriction-bearing at that point. 70

The breast-piece shown in Fig. 3 of the drawings, which is the form of breast-piece that I prefer to employ, is composed of the sleeve 16, which corresponds in all particulars to the same part of the breast-piece shown in Fig. 2; but in this case I substitute for the knob 17 a curved bar 20, and upon said bar 20 I mount a curved metallic breastplate 21, the said breastplate being secured in position upon the face of the bar 20 by bolts 22 22, which 80 pass through the curved bar 20, spiral springs 23 23, which are socketed in holes 24 24 in the bar 20, surrounding the screws and serving to maintain the breastplate 21 resiliently at a short distance from the bar 20. The lower 85 end of the brace carries a chuck 25, the said chuck being formed with a screw-threaded cavity in its upper end that receives the screw-threaded lower end 26 of the brace, the chuck when in position bearing against a shoulder 90 27 and being secured in position by means of a sliding pin 28. The pin 28 passes through the shoulder 27 and when the chuck is screwed home on the shank enters a hole in the chuck and holds it against rotary movement. A 95 small spiral spring surrounds the pin 28 and serves to impel it into the hole in the chuck. The chuck 25 is provided with the movable jaws 29 29, which are adjusted in the ordinary manner by a screw-ring 30. 110

The brace, as shown in Fig. 1, when fitted with either the brace-knob shown in that figure or with the breast-piece shown in Fig. 3, is adapted to be used in the manner of any ordinary brace, such as the brace commonly used 105 by carpenters or machinists for holding augers, drills, and the like.

In Fig. 4 of the drawings I have illustrated a sectional coal-drill adapted to be used by miners in connection with the parts shown in 110 Fig. 1, the said drill being composed of the bit 38, which has a shank 39, that is formed

with a screw-threaded cavity 40, adapted to receive the screw-threaded end 26 of the brace or when it is desired to lengthen the drill to receive the screw-threaded end 41 of an extension-piece 42, which has on its other end a screw-threaded hole 43, that is also adapted to receive the screw-threaded end 26 of the brace.

While my improved brace is adapted to be used in the same manner and for the same purpose as ordinary braces, in which event the knob 17 and chuck 25 may be arranged on the brace as shown in Fig. 1, I prefer to employ in connection with my improved brace the miner's boring-tool, (shown in Fig. 4,) and I also prefer to employ the breast-piece shown in Fig. 3, as the boring of holes in coal entails the exertion of considerable pressure on the breast-piece of the brace, and in braces of the ordinary character this pressure is very difficult to maintain, owing to the shocks and vibrations that are conveyed to the person using the brace through the breast-piece.

With my improvements the spring-sustained breastplate 21 entirely obviates the communication of vibrations and jarring motions to the person using the drill.

The improved handle above described with these ball-bearings constitutes an important adjunct of my brace, as it almost entirely obviates any friction between the handle and the crank portion of the brace and renders the same very much easier to operate than where handles of the ordinary character are employed.

Having described my invention, I claim—

1. The combination in a brace, of an angular one-piece shank and a handle consisting of a single section of material, the said handle having annular grooves in its inner wall, holes opening into said grooves, balls located in said grooves and means for closing the holes after the balls are introduced and the said shank having grooves corresponding to the grooves in the handle.

2. In a brace, a shank having a screw-threaded end and a shoulder adjacent said end, said end being adapted to receive a chuck having

a screw-threaded socket with a spring-pressed pin passing through the shoulder and adapted to engage the chuck.

3. In a brace, the combination with a one-piece shank, having a cranked portion, of a one-piece handle mounted on said cranked portion and revoluble thereon, and sustained against longitudinal movement by grooves in the shank, corresponding grooves in the handle, and interposed balls.

4. In a brace, a shank having a crank portion formed exclusively by bending the shank and of even diameter between the bends, said crank portion being provided with a plurality of circumferential grooves, in combination with a handle consisting of a single piece of metal pierced for the passage of the shank and provided with grooves in its bore, located wholly inside the ends of the handle and spaced apart a distance equal to the spacing of the grooves in the shank and balls located in the ways formed by the coinciding grooves in the shank and handle.

5. In a brace, the combination with a shank having a shoulder near its end and a screw-thread exteriorly of the shoulder, a pin passing through the shoulder, a spiral spring surrounding said pin and impelling the pin through the shoulder, of a chuck having a screw-threaded cavity in its end, to receive the threaded end of the shank and a hole adjacent said cavity to receive said pin.

6. In a brace, the combination of a shank, a sleeve revolubly mounted on the shank, means for maintaining the sleeve on the shank, a curved bar carried by said sleeve, a curved metallic breastplate, bolts having nuts countersunk in said breastplate and heads disposed on the outer side of said bar, and spiral springs interposed between the breastplate and said bar and seated in recesses in said bar.

In testimony whereof I affix my signature in the presence of two witnesses.

ZACCHEUS SCOTT.
